FIG. 12

FIG. 13

FIG. 1 is a side view of a soap dish holder incorporating my new design.

FIG. 2 is a top view of the soap dish holder.

FIG. 3 is a sectional view taken along the line 3-3 in FIG. 2.

FIG. 4 is an end view as seen from the right in FIG. 1.

FIG. 5 is a sectional view taken along the line 5-5 in FIG. 2.

FIG. 6 is a sectional view taken along the line 6-6 in FIG. 2.

FIG. 7 is a fragmentary sectional view taken along the line 7-7 in FIG. 2.

FIG. 8 is a fragmentary sectional view taken along the line 8-8 in FIG. 2.

FIG. 9 is a fragmentary sectional view taken along the line 9-9 in FIG. 2.

FIG. 10 is a fragmentary sectional view taken along the line 10-10 in FIG. 2.

FIG. 11 is a plan view of a modified form of soap dish holder incorporating my new design with the sections being the same as shown in FIGS. 7 and 8 and the end configurations being the same as shown in FIGS. 3 and 9.

FIG. 12 is a side view of the modified soap dish holder as seen from the bottom of FIG. 11.

FIG. 13 is a sectional view taken along the line 13-13 in FIG. 11.

The portions shown in broken lines are for purposes of illustration only.

This application is a division of my co-pending application Ser. No. 149,121, filed June 1, 1971.

I claim:

The ornamental design for a soap dish holder, as shown and described.
